THUMB PIECE FOR AN ENTRY LOCK

Raymond U. H. Tegner, Lodi, Wis., assignor to
Amerock Corporation, Rockford, Ill.

Filed Dec. 26, 1973, Ser. No. 430,948

Term of patent 14 years

Int. Cl. D8—07

U.S. Cl. D8—134

FIG. 1 is a front view of a thumb piece for an entry lock incorporating my new design.

FIG. 2 is a side view of the thumb piece as seen from the right of FIG. 1.

FIG. 3 is a bottom view of the thumb piece.

FIG. 4 is a top view of the thumb piece.

FIG. 5 is a rear view of the thumb piece.

FIG. 6 is a sectional view taken along the line 6—6 in FIG. 1.

I claim:

The ornamental design for a thumb piece for an entry lock, as shown.
